SAFETY DEVICE

August C. Brill, Oberursel, near Frankfort-on-the-Main, Germany, assignor to The Turner Tanning Machinery Company, Portland, Maine, a corporation of Maine

Application January 9, 1933. Serial No. 650,797
In Germany February 26, 1932

23 Claims. (Cl. 192—134)

This invention relates to safety devices for machines of various types and more particularly to guards for presses. It is to be understood, however, that the invention and various important features thereof may have other applications and uses.

While many different forms of guards have heretofore been proposed for preventing access of the operator's hands to the space between the co-operative platens of a press in operation, certain disadvantages have made the greater number of such guards unacceptable to the industry while many now in commercial use are not entirely satisfactory. It is not uncommon, for instance, for the guard to be so arranged that in moving from its inoperative position to its operative or protective position it comes forcibly into contact with the work in such manner as to mar the surface of the latter. Not a few of these guards are designed to strike the hands of the operator, as a warning and/or as a means for moving the hands from the danger zone. The blow upon the hand of the operator is sufficient to cause considerable discomfort, so much so that many operators refuse to use the guard and hence it is either removed or secured in inoperative position. In still other cases the guard is moved manually to operative or protective position. This is apt to slow up the operation of the press particularly in those instances wherein the guard is locked in its protective position. Furthermore, in certain types of hydraulic presses the operator may reverse at will the direction of movement of the movable platen, the said platen being moved away from pressure applying position substantially just far enough to release the work so that the latter may be shifted to a new position, whereupon the movable platen is again caused to engage the work in a second pressure applying operation without having returned to normal work receiving position. Such presses are apt to be specially dangerous to operate merely because of the ease and rapidity with which the movable platen may be caused to release the work and then almost instantly moved to effect a pressure applying operation. So far as I am aware, no satisfactory guard has heretofore been provided for this type of press.

Objects of this invention are to provide a safety arrangement for presses which will be simple and durable in construction and highly efficient for the purpose intended. Other objects are to avoid marring of the surface of the work and to provide for such operation of the safety device as to interfere as little as possible with the operator and with efficient operation of the press from the standpoint of production.

To these ends and in accordance with an important feature of the invention means is provided for locking a guard for a press in protective

relation with respect to the space between the relatively movable platens of the press, and maintaining it locked while it moves with one of the platens during a pressure applying operation. Preferably the guard when in operative position bears a predetermined spaced relation to the lower platen so as not to injure the work thereon, means being provided to maintain this spaced relation during movement of the guard with the movable platen in a pressure applying operation. By this arrangement the guard will not be moved to a position where it may mar the surface of the work. Furthermore, the arrangement is such that the guard is locked against displacement by the operator even though it is moving upwardly with the lower platen while the latter operates to effect a pressure applying operation in co-operation with the upper platen. Hence, the guard is operative throughout the operative stroke of the movable platen to protect the operator against the possibility of injury. At the end of the upward stroke of the platen the guard arrives at its inoperative position where it is held, provided it is unlocked, while the lower platen returns to work receiving position. Hence, the work may be removed as soon as the lower platen starts its downward movement and a fresh piece of work introduced the instant that the lower platen returns to its work receiving position, this arrangement contributing to the ease and facility of operation of the machine and hence to its productive capacity, in spite of the fact that the guard must be moved manually to its operative position.

In the illustrated construction, the means for locking the guard in its operative or protective position comprises a latch member which is bodily movable with the movable platen of the press so that the guard remains locked against movement to non-protective position relative to the movable platen while it moves with the latter during a pressure applying operation. In a preferred form of the invention the guard is supported by means comprising a lever which is weighted slightly more than to counterbalance the weight of the guard the arrangement being such as to cause movement of the guard to inoperative position while at the same time offering the minimum of resistance to movement of the guard to operative position in an organization wherein the weighted lever is arranged to return the guard to inoperative position with the movement of the movable platen while said guard is under control by the described latch member which prevents the guard from moving to non-protective position with relation to the movable platen during the operative stroke of the latter. Conveniently also the latch member for the guard is mounted on the lower platen of the press and is directly connected to the start-

ing means for the press in an arrangement by which the starting means cannot be moved to initiate operation of the press until said latch member has reached locking or latching position 5 to hold the guard in operative or protective position with respect to the space between the platens.

The guard, as herein disclosed, is particularly advantageous in connection with hydraulic presses of the type wherein the direction of movement of the movable platen may be reversed at will by the operator at any point in the upward or in the downward movement of said movable platen, without the necessity of returning the movable platen to its fully spaced relation with respect to the other platen which is its normal work receiving position. The purpose of such incomplete up and down movements of the lower platen is to release the work to permit shifting thereof to a new position followed by a renewed application of pressure. To accomplish these movements of the platen the starting means is moved through a restricted path, at no time far enough in one direction to effect locking of the starting means in its inoperative position nor release of the guard. Hence the illustrated guard will be maintained in its locked relation to the movable platen of such hydraulic press during repeated up and down movements of the movable platen and will only be released when the movable platen has returned to its normal work receiving position.

These and other important features of the invention and novel combinations of parts will now be described in detail and then pointed out more particularly in the appended claims.

In the drawing,

Fig. 1 is a side elevation of a press with the wire guard in inoperative position and the lower platen at rest in work receiving position; and

Fig. 2 is a horizontal section on the line II--II of Fig. 1 looking downwardly.

In the illustrated machine, designed particularly to perform smooth-plating and embossing operations upon pieces of leather, there is provided a C-shaped standard 4 which carries at the top a stationary plate or platen 6 adapted to be heated in the usual manner. Below platen 6 is arranged a hydraulic cylinder 8 in which is movably mounted a ram 12. On the ram rests 50 a lower press plate or platen 14 surrounded by an obliquely sloping wooden table 16.

Upon the hydraulic cylinder 8 at the front of the machine there is mounted a valve block 18, which also contains a control valve 20, arranged 55 to be operated by means of spur ratio gears 22 and a lever 24 manually operable by the operator in initiating and terminating pressure applying operations. For a more complete disclosure of a press of the type illustrated herein reference 60 may be had to United States Letters Patent No. 1,932,556, granted October 31, 1933, upon an application filed in the name of Paul V. J. Merenda.

The new safety device comprises a wire guard 26 which, in the construction shown, is arranged 65 to cover the dangerous space between the platens 6 and 14 at the front of the machine and at both sides. Two bell-crank levers 28 mounted on the upper platen 6 carry the front portion of the wire guard 26, its rear portion being pivotally supported on two other bell crank levers 30 keyed 70 to a shaft 32 passing across the back of the machine. The front and rear bell crank levers on each side are joined by a draw bar 34, so that pressure exerted from above at any point on 75 the wire guard 26 effects a lowering of the guard

without angular displacement thereof. To a third arm of the bell crank lever 30, as shown in Fig. 1, is pivoted a connecting rod 36, with a turnbuckle 38, having at its other end a pivotal connection with a double-armed lever 40. One end of the lever 40 is pivotally connected with a sleeve 42 adapted to slide along a vertically arranged rod 44. Since the rod 44 has a slight rocking movement in performing its other function in the press, the lever 40 has a pin and slot connection with the sleeve 42. This sleeve 42 serves as a stop for co-operation with a latch 46 pivotally mounted on the lower platen 14 and movably connected by a link 48 with the lever 24. In all positions but one the sleeve or stop 42 holds the latch 46 to the right of the rod 44 in Fig. 1 and thus holds the starting lever 24 in inoperative position. Hence operation of the control lever 24 is controlled by the position of the latch member 46, it being understood that the lever 24 is 20 the starting and stopping lever of the illustrated hydraulic press. In the full line position shown in Fig. 1, the sleeve 42 prevents movement of the latch 46 toward the front of the machine and thus prevents movement of the control lever 24 from 25 its inoperative position shown in full lines in Fig. 1. However, when the sleeve or stop 42 is moved to dotted line position by complete depression of the guard 26, the latch 46 is released by the stop 42 and the lever 24 may be 30 moved toward the front of the machine to start the press in operation.

The leverage of the system of levers (40, 36, 30, 34, 28) is preferably so chosen that the wire guard 26 moves upwardly with exactly the same speed 35 as the ram 12. By means of the turnbuckle 38 interposed in the connecting rod 36 it is possible to adjust the wire guard 26 in such a way that in the working position it stands a few millimetres only above the table 16, i. e. at such a short distance above the latter that it is impossible to place the hand underneath it, but, on the other hand, so far away from it that the leather cannot be damaged by the pressure of the wire guard 26. So long as the guard is maintained in operative 40 or protective position with respect to the space between the platens 6 and 14, the ram 12 may be raised and lowered as often as desired by manipulating the control lever 24. The arrangement is such, however, that the dangerous space 45 between the platens 6 and 14, must remain enclosed at all times. A counterweight 52 at one end of the lever 40 takes care that the wire guard 26 ascends automatically as soon as the latch 46 releases the sleeve 42, the latter then sliding upwards along the rod 44. Furthermore, counterweight 52 keeps the sleeve 42 against the lower end of latch 46 when the latter is in its operative position. Hence the sleeve 42 moves upwardly with the latch 46 as the lower platen 14 moves 50 upwardly, upward movement of the latch being accompanied by upward movement of the guard 26 in its spaced relation to platen 14.

The safety device functions in the following manner. When the control lever 24 is in the full line position shown in Fig. 1, the wire guard 26 is held in raised position by the weighted lever 40 and the operator can put both hands into the space between the platens 6 and 14, in order to place a piece of leather upon the lower press 65 plate 14 and to smooth it down. Accidental contact with the control lever 24 cannot turn it into working position, because when the wire guard 26 is raised the sleeve 42 is carried upwards to a 70 position where it prevents forward motion of the 75

latch member 46 and hence of the control lever 24 connected thereto. Only when the operator presses the guard 26 fully down with his left hand is he able to operate the control lever 24 with his

5 right hand, because the sleeve 42 is then in position to permit movement of latch member 46 to the left as indicated in broken lines in Fig. 1. On turning the control lever 24 fully to the left in Fig. 1 to initiate a pressure applying operation, the latch 46 is drawn so far forward by the link 48 that latch 46 is positioned above the sleeve 42 and thus locks the guard 26 against separating movement relative to the lower platen 14 while it participates in the ascent of the platen, on 10 which the latch 46 is pivotally mounted. During the up and down movements of the sleeve 42, due to the weighted lever 40 and to the latch 46, the wire guard 26 is caused to move up and down simultaneously with the lower press platen 14, while being maintained in slightly spaced parallel relation to said platen, and it will only be released again when the operator forces the control lever 24 back into its extreme position of rest at the right in Fig. 1 in which the sleeve 42 is released 15 by the latch 46 so that both sleeve 42 and guard 26 may be moved upwardly by the weighted lever 40. In other words, the lower platen 14 may be caused to make incomplete up and down movements to permit repeated shifting of the work on the lower platen between pressure applying operations. To accomplish this result, the control lever 24 is moved only part way to solid-line position from its dotted-line position and then back to dotted-line position. Such movement of the 20 control lever does not release the guard 26. Movement of the lever 24 to solid-line position will effect return of the lower platen 14 to work receiving position and also release of the guard 26 which at once moves to its inoperative or non-protective position. This means that the stop 25 sleeve 42 is released by latch 46. Movement of the stop sleeve 42 upwardly on the rod 44 brings it quickly to a position where it will arrest sidewise movement of the latch 46 and thereby holds the starting lever 24 in inoperative position.

In case the press is being served by two workers and a hand of either worker is still in the dangerous space between the platens when the operator at the control lever 24 attempts to force 30 down the wire guard 26 and to start the machine in operation, it will be found that the control lever 24 cannot be moved into the position in which the hydraulic pressure becomes operative, because the hand between the wire guard 26 and the platen 14 or table 16 prevents a complete downward movement of the guard. Hence the sleeve 42 cannot move sufficiently far in a downward direction 35 on the rod 44 to release starting the lever 24, until the hand is removed from its dangerous position. As already pointed out the embodiment described and shown in the accompanying drawing is merely an example for the construction of the machine, and alterations and modifications are possible without departing from the scope of the 40 following claims.

Having fully described my invention, what I claim as new and desire to secure by Letters Patent of the United States is:

1. In a press having two platens one of which 45 is movable with respect to the other to effect pressure applying operations, a guard movable between operative and inoperative positions with respect to said platens, said guard being of a size to cover, when in operative position, the entire 50 space between the platens at rest in open posi-

tion and being mounted for movement with the movable platen while maintaining its protective relation to the space between the platens, and means arranged to lock the guard in operative or protective position during movement of the movable platen in a pressure applying operation. 5

2. In a press having two platens one of which is movable with respect to the other to effect pressure applying operations, a guard movable between operative and inoperative positions with respect to said platens, said guard being mounted for movement with the movable platen while maintaining its protective relation to the platens, and means movable with the movable platen of the press to lock the guard in operative or protective position during movement of the movable platen in a pressure applying operation. 10

3. In a press having two platens one of which is movable with respect to the other to effect pressure applying operations, a guard movable between operative and inoperative positions with respect to said platens, and a latch member mounted on the movable platen of the press and arranged to lock the guard in operative or protective position during movement of the movable 15 platen in a pressure applying operation. 20

4. In a press having two platens one of which is movable with respect to the other to effect pressure applying operations, a guard movable between operative and inoperative positions with respect to the space between said platens, and a latch member arranged to lock the guard in its operative or protective position, said guard and said latch being both bodily movable with the movable platen so that said guard is maintained 30 in its protective relation to the movable platen during a pressure applying operation. 35

5. In a press having two platens, one of which is movable with respect to the other to effect pressure applying operations, a guard movable between operative and inoperative positions with respect to the space between said platens, and a latch member arranged to lock the guard in operative or protective position with respect to the space between the platens of the press, said latch 40 member being bodily movable with the movable platen during the closing of the press to permit movement of the guard at the same rate as the closing movement of the press while maintaining the guard locked in its operative or protective 45 relation to said platens. 50

6. In a press having two platens one of which is movable with respect to the other to effect pressure applying operations, a guard movable between operative and inoperative positions with respect to the space between said platens, a latch member, and a stop member connected to the guard and arranged to be moved to a position to co-operate with the latch member to lock the guard in its operative or protective position, said 55 latch member and said stop member being movable with respect to one of the platens of the press and at a rate the same as that of the closing movement of the press to maintain said guard in locked condition during the closing of the 60 press. 65

7. In a press having two platens one of which is movable with respect to the other to effect pressure applying operations, a guard movable between operative and inoperative positions with respect to said platens, means arranged to locate the guard, when in operative position, in spaced relation to a piece of work on the lower platen of the press, a latch member arranged to lock the guard in its operative or protective position, said 70 75

latch member being movable with respect to one of the platens of the press and at a rate the same as that of the closing movement of the press, and means to move the guard with the latch member so that said guard is maintained in locked condition and in the desired spaced relation to the work during the closing of the press.

8. In a press having two platens one of which is movable with respect to the other to effect pressure applying operations, a guard movable between operative and inoperative positions with respect to said platen, means arranged to locate the guard, when in operative position, in spaced relation to a piece of work on the lower platen of the press, a latch member, a stop member connected to the guard and arranged to be moved to a position to co-operate with the latch member to lock the guard in its operative or protective position, said latch member being movable with respect to one of the platens of the press and at a rate the same as that of the closing movement of the press, and means to move the guard with the latch member so that said guard is maintained in locked condition and in the desired spaced relation to the work during the closing of the press.

9. In a press having two platens the lower of which is movable with respect to the other to effect pressure applying operations, a guard movable between operative and inoperative positions with respect to the space between said platens, a latch member movable with the movable lower platen and operative to lock the guard against separating movement with respect to said lower platen, and means arranged to support the guard and to cause it to move with said movable platen during upward movement of the latter, whereby the guard is maintained in protective position during movement of the movable platen toward and from the other platen.

40 10. In a press having two platens the lower of which is movable with respect to the other to effect pressure applying operations, a guard movable between operative and inoperative positions with respect to the space between said platens, a latch member bodily movable with the movable lower platen and operative to lock the guard against separating movement with respect to said lower platen, and a weighted lever arranged to support the guard and to cause it to move with said movable platen during upward movement of the latter, whereby the guard is maintained in protective position during movement of the movable platen toward and from the other platen.

55 11. In a press having two platens one of which is movable with respect to the other to effect pressure applying operations, a guard movable between operative and inoperative positions with respect to said platens, means movable with the movable platen to lock the guard in its operative position, a starting mechanism for the press comprising a manually operable member, and a connection between said manually operable member and the locking means arranged to move the latter selectively to operative position to lock the guard in its protective position and to inoperative position to release said guard.

60 12. In a press having an upper platen and a lower platen movable upwardly to effect pressure applying operations upon pieces of work supported by the lower platen, a guard movable between operative and inoperative positions with respect to the space between the platens, the work upon the lower platen being supported in such manner as to be directly in line with the movable 70 guard, means arranged to locate the guard, when 75

in operative position, in spaced relation to the piece of work on the lower platen, and means to cause the guard to travel upwardly with the lower platen while maintaining such spaced relation thereto whereby the guard is maintained in its operative relation during upward movement of the lower platen. 5

13. In a press having an upper platen and a lower platen movable upwardly to effect pressure applying operations, a safety device comprising 10 a guard movable between operative and inoperative positions with respect to the space between the platens, means arranged to locate the guard, when in operative position, in spaced relation to a piece of work on the lower platen of the press, a 15 starting mechanism for the press, connections between the guard and the starting mechanism arranged to lock the guard in its operative position, and means arranged to cause the guard to travel upwardly with the lower platen while maintaining said spaced relation thereto whereby the guard is maintained in its operative position during 20 upward movement of the lower platen.

14. In a press having platens relatively movable with respect to each other to effect pressure applying operations, a guard movable between operative and inoperative positions with respect to the space between said platens, a member connected to said guard and guided for vertical movement during movement of the guard, a latch 30 member movable to a position vertically over said member to lock the latter against vertical movement thereby to lock the guard in its operative position, starting mechanism for the press comprising a manually operable member, and a connection between said manually operable member and the latch member arranged to hold said manually operable member so that the latter cannot be moved while the guard is out of protective or operative position. 40

15. In a press having an upper platen and a lower platen movable upwardly with respect to the upper platen to effect pressure applying operations, a guard movable between operative and inoperative positions with respect to the space between said platens, a latch member mounted on the movable lower platen and arranged to lock the guard in its operative position, starting mechanism for the press comprising a manually operable member, and a connection between said manually operable member and the latch member arranged to hold said manually operable member against operation while the guard is out of protective or operative position. 45 50

16. In a press having two platens one of which is movable with respect to the other to effect pressure applying operations, a guard movable between operative and inoperative positions with respect to said platens, a starting mechanism for the press comprising a manually operable member, a latch member movable into position to lock the guard in its operative position, and a connection between the latch member and said manually operable member whereby the former may be moved to locking position by the latter, said 60 latch member being mounted for movement at the same rate as one of the platens whereby the guard is permitted to move with said movable platen to maintain its operative position during the closing of the platens in a pressure applying 65 operation. 70

17. In a press having platens relatively movable with respect to each other to effect pressure applying operations, a guard movable between operative and inoperative positions with respect 75

- to said platens, a starting mechanism for the press comprising a manually operable member, a latch member, a stop member connected to the guard and arranged for cooperation with the latch member in holding the guard in operative position, said stop member being also operative to hold the latch member in unlatching position while the guard is in inoperative position, and a connecting member between the latch member and said manually operable member to hold the latter in its inoperative position whereby the manually operable member cannot be operated to initiate operation of the machine while the guard is in inoperative position.
18. In a press having two platens one of which is movable with respect to the other to effect pressure applying operations, a guard movable between operative and inoperative positions with respect to said platens, a stop member connected to the guard, a starting mechanism for the press comprising a manually operable member, a latch member arranged to co-operate with the stop member to lock the guard in its protective or operative position, and a connection between said manually operable member and said latch member for moving the latter selectively to latching or unlatching position with respect to said stop member, said latching member being movable to permit the guard to move with the movable platen during the closing of the press while maintaining said guard in its locked relation during said closing of the press.
19. In a press having platens relatively movable with respect to each other to effect pressure applying operations, a guard movable between operative and inoperative positions with respect to the space between said platens, a stop member connected to said guard, said stop member being movable upwardly and downwardly with the movement of the guard, a latch member movable into position above the stop member when the guard is down in its protective or operative position whereby the stop member and latch member co-operate to lock the guard in its protective position, means to move said latch member vertically at the same rate as that of the closing of the press, and means to cause the stop member to move with the latch member whereby the guard is caused to move vertically during the closing of the press while maintaining its protective relation with respect to the space between the platens of the press.
20. In a press having two platens one of which is movable with respect to the other to effect pressure applying operations, a guard movable between operative and inoperative positions with respect to said platens, a stop member connected to the guard, a latch member for co-operation with the stop member in holding the guard in locked relation to the space between the platens of the press, and means arranged to hold the stop member in contact with the latch member, said latch member being mounted on the movable platen of the press and said last-mentioned means being operative to move the guard upwardly with the upward movement of said movable platen whereby the guard, while moving upwardly, is maintained in the desired spaced relation with respect to said movable platen through the co-operation of the latch member and the stop member.
21. In a press having two platens one of which is movable with respect to the other to effect pressure applying operations, wherein hydraulic
- means is provided for causing approaching and retracting movements of the platens with respect to each other at the will of the operator, a guard movable between operative and inoperative positions with respect to the space between said platens, a latch member bodily movable with the movable platen and operative to lock the guard against separating movement with respect to said movable platen, and means to cause the guard to move with said movable platen during movement of the latter to effect a pressure applying operation, whereby the guard is maintained in protective position during repeated movements of the movable platen toward and from the other platen in the intervals of its return to normal work receiving position.
22. In a press having a stationary and a movable platen, wherein hydraulic means is provided for causing relative movements of approach and also of retraction of the platens with respect to each other in an organization wherein the movements of the movable platen may be reversed at will by the operator in the intervals of the return of said movable platen to its fully spaced relation to the other platen, a guard movable between operative and inoperative positions with respect to the space between said platens, a latch member mounted on the movable platen and operative to lock the guard against separating movement with respect to said movable platen, and means comprising a member connected to the guard and co-operating with the latch member to cause the guard to travel in one direction with the movable platen, the latch member being arranged to cause the guard to move in the other direction with the movable platen, whereby the guard is maintained in protective relation to the space between said platens during both up and down movements of the platens with respect to each other.
23. In a press having an upper platen, a lower platen movable upwardly into co-operative relation to the upper platen to effect pressure applying operations, hydraulic means for causing relative movements of approach and also of retraction of the platens with respect to each other in an organization comprising a manually operable member for controlling said hydraulic means whereby movement of the lower platen may be reversed at will by the operator without the return of said lower platen to its normal work receiving position, the combination of a guard movable between operative and inoperative positions with respect to the space between said platens, a latch member mounted on the movable lower platen and operative to lock the guard against separating movement with respect to said lower platen, a connection between the manually operable member and the latch member arranged to hold the latch member in guard-locking position while the manually operable member is in position to cause up and down movements of the lower platen without returning the lower platen to work receiving position, and a weighted member connected to the guard and co-operating with the latch member to cause the guard to travel upwardly with the movable lower platen, the latch member causing the guard to move downwardly with the movable lower platen, whereby the guard is maintained in protective relation to the space between said platens during both up and down movements of the platens with respect to each other.
